UNITED STATES PATENT OFFICE

OTTO BANKER, OF MANKATO, MINNESOTA

DRAIN BOARD FOR WRINGERS

Application filed March 25, 1930. Serial No. 438,824.

This invention relates to a drain board for use in connection with wringers.

It is frequently desirable to place a clothes wringer between two tubs and to pass the fabrics from one tub through the wringer to the other tub. During this operation the expressed water should be directed back to the tub from which the fabrics were removed. It is an object of the present invention to provide a wringer with a reversible drain board which can be quickly positioned to direct the water into either tub.

Another object is to provide novel means for holding the drain board in either of its two extreme positions.

A still further object is to provide a structure of this character which is simple, durable, and compact and can be combined readily with a wringer.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a front elevation of a portion of a wringer provided with the present improvement.

Figure 2 is a side elevation.

Figure 3 is a section on line 3—3, Figure 1.

Referring to the figures by characters of reference, 1 designates the frame of a wringer which is adapted to be set up between two tubs. The rolls have been indicated at 2 and can be driven by any suitable means.

Secured within the frame 1 below the rolls 2 are plates 3 extending throughout the length of the rolls and attached to the inner faces of cross strips 4. Each of these plates is provided at its upper edge with a deflecting flange 5. The two flanges carried by the two plates are oppositely disposed and in-

clined downwardly toward each other to positions under the lower roll 2.

A rod 6 is arranged beneath the space between flanges 5 and fastened to this rod so as to be supported thereby and to rotate therewith is a drain board 7.

A crank arm 8 is provided at one end of rod 6 and is supported back of a guide plate 9 the ends of which are offset as at 10 and attached to frame 1. In this plate is an arcuate slot 11 concentric with the axis of rod 6 and the free end portion of crank arm 8 extends through this slot and may be provided with a knob 12 or the like.

The parts are so proportioned that when the crank arm is positioned in one end of slot 11 the drain board 7 is inclined so that its upper edge bears against the lower surface of one flange 5. Consequently when water expressed from fabrics flows downwardly along the lower roll 2 it will be deposited on the two flanges 5 and be deflected thereby onto the drain board 7 which, in turn, will direct the water by gravity from the selected side of the frame 1. By shifting the crank arm 8 to its other extreme position the position of the drain board will be reversed and the extracted water will be delivered from the other side of the frame.

Frictional contact between the crank arm 8 and plate 9 will be sufficient to hold the drain board in place. It will be noted that the drain board is practically concealed at all times between the cross strips 4 and has no part projecting outwardly from the frame where it might be in the way of a person working adjacent to the wringer.

As will be obvious by referring to Figure 3, the lower edge of the drain board 7 is located between the lower portions of the strips 4 when the drain board is in either of its extreme positions. Consequently any suitable volume of water draining downwardly along the board will be deflected downwardly by the adjacent lower portion of the strip 4 or 90 of the plate 3 attached thereto.

What is claimed is:

1. The combination with a wringer frame and rolls therein, of oppositely disposed downwardly converging water-deflecting

- members beneath the rolls, cross strips, a drain board tiltably mounted beneath said members and substantially concealed at all times between the cross strips, and means for tilting the drain board into contact with the bottom surface of either of said members, the distance between the upper and lower edges of the drain board being less than the distance between the cross strips, the lower portion of each of said cross strips constituting
- 10 water deflecting means.
2. The combination with a wringer frame and rolls therein, of spaced cross strips having lower deflecting portions oppositely disposed downwardly converging water-deflecting members beneath the rolls and secured to the cross strips, a drain board tiltably mounted beneath said members and substantially concealed at all times by the cross strips, and means for tilting the drain board into
- 15 contact with the bottom surface of either of said members, said means including a crank arm fixed to the drain board and a guide for limiting the swinging movement of the crank
- 20 arm.
- 25 In testimony that I claim the foregoing as my own, I have hereto affixed my signature.

OTTO BANKER.
